[57] CLAIM

The ornamental design for a hose coupling, as shown and described.

DESCRIPTION

FIG. 1 is a front perspective of a hose coupling showing my new design;

FIG. 2 is an upended front elevation thereof the opposite side appearing the same;

FIG. 3 is an inverted side elevation of FIG. 2;

FIG. 4 is a top plan of FIG. 2; and,

FIG. 5 is a bottom plan of FIG. 2.

The broken lines showing the inner structures of the coupling are for illustrative purposes only and form no part of the claimed design.
